UNITED STATES PATENT OFFICE.

MILTON DASHIELL, OF BALTIMORE, MARYLAND, ASSIGNOR OF TWO-THIRDS
TO JOHN W. WOODLAND, OF BALTIMORE, MARYLAND.

ELEVATOR.

No. 853,534.

Specification of Letters Patent.

Patented May 14, 1907.

Application filed December 18, 1905. Serial No. 292,320.

To all whom it may concern:

Be it known that I, MILTON DASHIELL, a citizen of the United States, residing at Baltimore, State of Maryland, have invented 5 certain new and useful Improvements in Elevators; and I do hereby declare the following to be a full, clear, and exact description of the invention, such as will enable others skilled in the art to which it appertains to 10 make and use the same.

This invention relates to elevators and more particularly to stops therefor and has for its object to provide means for preventing movement of an elevator car before the door 15 at which the car is located is closed, another object being to provide means for preventing the opening of the shaft doors at times other than when the car is at the door to be opened.

20 Other objects and advantages will be apparent from the following description.

In the drawings forming a portion of this specification and in which like numerals of reference indicate similar parts in the several 25 views, Figure 1 is an elevational view of a shaft door, part of the floor upon which the door opens being broken away to illustrate the casing of the stop mechanism. Fig. 2 is a top plan view of the stop mechanism, and 30 showing a section of the shaft on line 2—2 of Fig. 1, the car being shown in top plan as below the level of the floor. Fig. 3 is a vertical section taken on line 3—3 of Fig. 1, the sliding door being opened and the car being 35 in position at the landing. Fig. 4 is a detail horizontal section of the grooved disk carried by the controller. Fig. 5 is a detail perspective view partly in section, showing a modified structure in which the stop mechanism 40 is adapted for use in connection with a cable operated elevator. Fig. 6 is a detail top plan view of a modified form of stop mechanism.

Referring now to the drawings, there is 45 shown an elevator shaft 5 opening at its forward side upon a landing 6, half of the opening being closed by a stationary grating 7, while a sliding door 8 is arranged to lie at times in position to close the other half of the opening and at times to lie in inoperative 50 position and against the outer face of the grating 7. This door 8 lies, when in closed position, with its lower corner 9 adjacent to the lower inner corner of the grating 7 and the lower portion of the forward face of the

door 8 is cut away adjacent to its corner 9 to 55 form a cam surface 10 slanting from this corner outwardly toward the outer edge of the door for a purpose to be presently described. A roller 11 is journaled horizontally in the lower portion of the grating 7 and receives 60 the door 8 thereagainst to reduce the friction between the door and grating.

Located beneath the landing 6, there is a casing 7' in which there is pivoted for horizontal movement, a horizontally disposed 65 angle lever 12 having one end turned upwardly, as shown at 13, to extend through the landing 6 and thereabove and a horizontally journaled roller 14 is carried by this upwardly turned portion of the angle lever 70 and rests against the outer face of the door 8 at the lower portion thereof. The angle lever includes two arms 12' and 12'', the former being that which has the upwardly turned end portion 13, and the arm 12'' extends in a direction generally parallel with the grating 7 and has the pivot point of the lever located therein to a point spaced from its union with the arm 12'. The arrangement is thus such that when the door 8 is moved 75 into open position, the roller 14 lying in engagement with the cam surface 10 of this door, will be moved with the arm 12' of the angle lever forwardly away from the shaft 5, which will move the free end of the arm 12'' 80 toward the shaft, as will be readily understood.

A plunger 15 is located within the casing 7' and extends toward the shaft, this plunger having a finger 16 and being movable slidably to bring the free end of the finger into and out of the shaft, and this plunger is located in position to receive the free end of the arm 12'' against its inner end. The plunger is slidably engaged in a guide 18, while the 90 finger 16 is similarly engaged in a guide 19 and engaged with this finger between the guide 19 and the plunger, there is a helical spring 17 which thus holds the plunger yieldably at the forward limit of its movement 95 and with the finger out of the shaft, the spring also holding the angle lever with the roller 14 tight against the cam surface of the door 8.

A car A is located in the shaft 5 and has a 100 controller 20 which includes a revoluble vertical rod 21 provided with an operating handle 22 at its upper end and extending at its

lower end through the floor of the car and having mounted thereupon beneath the floor a horizontal disk 23 having a vertical groove 24 in its periphery. This groove is so located that when the controller is in position to hold the car against movement, the groove lies in position to receive therewithin the finger 16 of the plunger. It will thus be seen that when the car is brought into position at 5 the landing 6, and is stopped, opening of the door 8 will move the finger 16 into the groove 24, and the finger will then extend beneath the floor of the car and through an opening 25 formed in a face plate 26 which extends 10 above and below the floor of the car and which also acts as a support for the controller 21. If it be now desired to raise or lower the car, the door 8 must first be closed to bring the fingers 16 out of the groove 24, so that 15 the controller 20 can be moved.

The grating 7 has an opening 27 therein and pivoted in brackets 29 carried by the landing 6 within the shaft 5, there is a vertically extending latch 30 having a nose 31 20 movable into and out of position to extend through the recess 27 and into the path of movement of the door when the latter is opened when the latch is moved upon its pivot. The nose is located above the pivot 25 point of the latch, and the latter extends below its pivot point and has a roller 32 journaled therein at its lower end, the roller extending vertically and into the shaft beyond the latch, the inwardly extending portion of 30 the roller lying in the path of movement of a cam block 33 carried by the car. A spring 34 is disposed to hold the latch yieldably with its nose 31 in the opening 27. The cam block 33 is so disposed that it lies in engagement 35 with the roller 32 to hold the latch 30 in inoperative position when the car is at the landing 6 and it will thus be apparent that the door 8 may be opened only when the car is in such position.

40 In the modified form of the invention shown in Fig. 5, the stop mechanism is adapted for use in connection with a cable operated elevator. In this form of the invention, a stem *a* corresponds to the finger 16 and has a 45 yoke *b* at its end which is movable into the shaft and when this yoke is in the shaft, it lies with its spaced legs *c* at opposite sides of the operating cable *d* and between a pair of members *e* secured to the cable. Movement

of the cable when the yoke *b* is in its just described position, is prevented by engagement of the members *e* with the yoke and the car cannot be started until the door is closed, as will be readily understood, the stem *a* and yoke *b* being controlled by the door as in the 55 first described form.

In Fig. 6 there is shown a modified form of the invention in which a lever *Z* is pivoted between its ends and rests at one end against the plunger 15. The other end of the lever 60 receiving thereagainst one end of a slide *Y*, mounted in guides in the casing 7' and having its other end, which lies toward the door 8, turned upwardly as shown at *X* and having journaled therein a roller *W* corresponding 65 in arrangement and function to the roller 14.

What is claimed is:

The combination in an elevator including a shaft and a car movable in the shaft, of a 70 door for the shaft movable into and out of operative position, a movable controller in the car, a disk carried by the controller for movement therewith and having a notch therein, a finger mounted independently of 75 the car for movement into and out of position to engage in the notch, a plunger connected with the finger for movement therewith, a spring arranged to hold the finger yieldably out of position for engagement 80 with the notch, a pivoted lever engaging the plunger and movable to move the plunger against the action of the spring, means for moving the lever, said means including a roller disposed for engagement by the door 85 when the latter is moved into open position, to bring the finger into notch-engaging position, a latch pivoted independently of the car and having a nose movable into and out of position to hold the door in closed position, 90 and a spring arranged to hold the latch yieldably with its nose in operative position, said latch being arranged for engagement by the car, to hold the latch against the action of the spring when the car is in position to receive the finger in the notch of its disk.

In testimony whereof, I affix my signature, in presence of two witnesses.

MILTON DASHIELL.
